UNITED STATES PATENT OFFICE.

JOHN B. MOORE, OF OAKLAND, CALIFORNIA, ASSIGNOR, BY MESNE ASSIGNMENTS, TO THE MOORE IMPROVED GOLD SEPARATOR COMPANY, OF CALIFORNIA.

ORE-SEPARATOR.

SPECIFICATION forming part of Letters Patent No. 658,921, dated October 2, 1900.

Application filed December 21, 1899. Serial No. 741,162. (No model.)

To all whom it may concern:

Be it known that I, JOHN B. MOORE, a citizen of the United States, residing at Oakland, county of Alameda, State of California, have 5 invented certain new and useful Improvements in Ore-Separators; and I do hereby declare the following to be a full, clear, and exact description of the same.

The present invention is designed for use 10 in connection with the working of beach sand or gravel mining; and it consists in the arrangement of parts and details of construction, as will be hereinafter fully set forth and described in the specifications and pointed 15 out in the claims.

The object of the invention is to provide a machine whereby I am enabled to separate the precious material from the waste or worthless portion and to concentrate the precious 20 material thus separated in order to obtain or recover the precious metal carried thereby.

To comprehend the invention, reference should be had to the accompanying drawings, forming a portion of this application, 25 wherein—

Figure 1 is an end view in elevation of the machine viewed from its discharge end. Fig. 2 is a side view in elevation, the rotary separator being partly broken away. Fig. 3 is a 30 top plan view of the concentrating-table, the rotary separator and its connected parts being removed; and Fig. 4 is a detail view of one of the riffle-plates.

In the drawings, the letter A is used to indicate any suitable frame for the machine, the side pieces A' A² of which are arranged 35 at a slight inclination. Between these side pieces is mounted to swing the concentrating-table B, said table being supported by means 40 of shoulders a, projecting therefrom, working in guide-slots a' in the side pieces. To the under face of the concentrating-table, near its discharge end, are secured the rods B', which rods at their outer ends encircle 45 the eccentric cams B², mounted upon the cross-shaft B³, working in bearings of the side pieces. To one end of this cross-shaft is attached the pulley C, which receives motion from any suitable drive-motor through the

medium of drive-belt C', working thereover. 50 As the cross-shaft B³ is driven a longitudinally-reciprocating motion is imparted to the concentrating-table through the connecting-rods B' and eccentric cams B².

Within the sides 2 of the concentrating-table is trunnioned a series of riffle-plates b. 55 To the lower edge of each is attached a strip of rubber or canvas 3, which when the plates stand in a vertical position bear firmly upon the face of the table. These cross-plates divide the surface of the table into a series of riffles or pockets 4.

Outside of the side pieces A' A² are arranged 60 the slide-bars D D', which are attached to the frame-pieces at each end by the crank-levers D². These levers are fulcrumed to the side pieces, and the inner end of each terminates in toothed segment 5, which engages with a rack 6, attached to the sides of the table. Being thus connected the longitudinal motion of the table is imparted to the 65 slide-bars.

Between the riffle-plates b work the cross-rods 7, each being provided with a series of 70 depending fingers 8. These fingers work with 75 in the riffles or pockets 4 of the table and serve to agitate the sand or material therein. The end of one rod is held in bearing 9 of side piece A' and its opposite end turned or flanged downward and fitted within socket b' of slide-bar 80 D, while the next rod will have one end held in bearing 10 of side piece A² and its opposite flanged end resting in socket b² of slide-bar D. The rods are thus alternately connected to side piece A' and slide-rod D' and side 85 piece A² and slide-rod D. As thus connected the rods 7 move crosswise of the table during the reciprocating motion thereof. The fingers 8 work close to the riffle-plates b and slightly above the surface of the tables. The 90 riffle-plates are held locked in position by means of a turn-button d, which serves to prevent the plates being displaced during the working of the machine.

At the discharge end of the machine, below 95 the concentrating-table, is arranged the water-trough E, within which rotates the drum E'. Around the face of this drum the con-

caved amalgam-plates E^2 are secured, upon which plates the material discharged from the concentrating-table falls.

The object of the amalgamating-drum is to intercept any of the float-gold which might pass from off the concentrating-table during the aggregation of the pulp thereon by the finger-bars. Unless this amalgamating-drum be provided the said float-gold would be lost by reason of the violent agitation of the pulp upon the concentrating-table, as the same would be carried off by the water flowing thereover. The axle d' of the drum E' works in bearings of the frame A , and to one end of said axle is secured the sprocket-wheel E^3 .

Above the concentrating-table is suspended the rotary separator F , which is attached to the longitudinal shaft F' by arms F^2 . This shaft F' works in bearings of the cross-pieces G of uprights A and is driven by means of pinion f , meshing with bevel-gear f' , attached to one end of the said shaft. Pinion f is secured to cross-shaft G' , working in bearing-brackets attached to forward uprights.

The drum E' is driven from the cross-shaft through the medium of sprocket-chain G^2 , working over sprocket-wheel E^3 on axle d' and sprocket-gear G^3 , secured to one end of shaft G' . To the opposite end of this shaft is fastened sprocket-wheel H , and said shaft has motion imparted thereto from the drive-shaft B^3 by means of sprocket-chain H' , working over wheel H and sprocket H^2 , mounted upon drive-shaft B^3 .

To the feed end of the rotary separator is attached the imperforate inclined collar I , which receives the material to be treated from feed hopper or box I' . The object of this inclined collar is to hold the water within the rotary separator at a given level, for, as the separator is arranged at a slight rearward incline, without the employment of this collar the material fed into the separator would at once flow therefrom at its feed end. This collar acts as a retaining-wall to hold the material in the separator and maintain therein a proper amount of water. Of course this will be regulated by the pitch at which the separator is suspended and the inclination of the

collar. Within the interior of the separator there is secured a series of projecting fingers g , which fingers are arranged spirally from the collar I to near the discharge end of the separator, or to point x . These fingers, owing to their arrangement, serve as a worm to gradually feed the material toward the discharge end of the separator during the rotation thereof. From point x to discharge end of separator is arranged the spiral converging blade or worm I^2 , which acts to convey the material from within the separator onto the inclined screen J , secured to the discharge end of the separator. The fingers g are mainly employed to break up and disintegrate the material fed into the separator, although, owing to their spiral arrangement, they gradually force the material for-

ward, while the worm I^2 answers to retard the travel of the material and to discharge the disintegrated material from within the separator. As delivered to the screen portion J of the separator the finesand, dirt, and precious material passes through the mesh of the screen and falls into chute J' and is delivered to the upper end of the concentrating-table, upon the surface of which the final separation takes place as the material is gradually worked toward the discharge end thereof by the reciprocating motion imparted thereto by the described mechanism. The sand is kept agitated within the riffles or pockets of the table and prevented from settling and banking therein by the action of the stirrers or agitating-fingers 8 , which work crosswise therein by the lateral motion of the rods 7 . Whatever fine gold escapes from the table will be caught upon the amalgamating-plates carried by the rotating drum E' .

The stones, gravel, and coarser material delivered from the separator fall into discharge-chute K and are conveyed to a suitable place of deposit.

Water is supplied to the feed end of the rotary separator by pipe K' , leading from coupling l of stand-pipe K^2 . This stand-pipe connects with force-pump L , which pump is operated from drive-shaft B^3 by means of sprocket-chain L' , working over sprocket-wheel L^2 , secured upon the drive-shaft, and sprocket-wheel L^3 , secured to pump-shaft l' . To coupling l is connected the branch pipe M , which conveys water into the discharge end of the rotary separator in order to spray the material delivered upon the screen J , so as to thoroughly wash and separate the material while at the same time aiding the finer portions to pass through the screen.

When it is desired to make a clean-up, the cross-rods 7 are removed and the riffle-plates turned upward, so as to enable the operator to remove the precious metal from off the surface of the concentrating-table. The drum E' , with its amalgamating-plates E^2 , is removed from within the trough E and the plates freed of the amalgam gold. Contents of trough E may be drawn off in any suitable manner, as by opening outlet l^2 .

Having thus described my invention, what I claim as new, and desire to secure protection in by Letters Patent, is—

1. The combination of a longitudinally-reciprocating concentrating-table and a rotary imperforate cylinder having a tapering imperforate collar secured to its feed end, the axis of said cylinder being inclined upward from the feed toward the discharge, a tapering screen attached to its discharge end, a closely-set spiral line of fingers or projections on the inner surface of the imperforate cylinder and a spiral converging blade mounted on the inner surface of the tapering screen, whereby the desired depth of pulp is maintained and disintegrated within the cylinder, the coarser material is forced away from the

pulp and separately discharged and the finer material delivered to the surface of the concentrating-table.

2. The combination of a longitudinally-reciprocating concentrating-table and a rotary imperforate cylinder having a tapering imperforate collar secured to its feed end, the axis of said cylinder being inclined upward from the feed toward the discharge end of the cylinder, a tapering screen attached to its discharge end, a spiral set of fingers or projections arranged within the imperforate cylinder, the cylinder being arranged at an inclination, an inclined collar secured to the feed end of said cylinder, of means for supplying water to the interior of the said cylinder, and a chute leading from the discharge end of the cylinder to the concentrating-table, said chute conveying the separated material from the cylinder to the table.

3. In a machine of the described character, the combination with a rotary separator into which the material to be treated is fed, a longitudinally-reciprocating concentrating-table arranged below the separator, a chute leading from the discharge end of the separator to the upper end of the concentrating-table, a series of riffle-plates movably connected to the table and dividing its surface into riffles or pockets, a series of finger-bars arranged cross-wise of the table and working in said pockets, and means for imparting lateral motion to the finger-bars during the longitudinal movement of the concentrating-table.

4. The combination of a rotary separator which eliminates the coarse impurities, a chute or runway leading the finer pulp from the discharge end of the separator, a concentrating-table receiving the fine pulp from said chute, a series of transversely-moving agitators working across the upper surface of the concentrator and maintaining the suspension of the finer material while permitting the grain-gold to settle, a trough arranged

below the concentrating-table, a drum working therein and a series of amalgamating-plates secured to the drum and operating to intercept the float-gold escaping from the concentrating-table.

5. The combination with a concentrating-table, of means for imparting a longitudinally-reciprocating motion thereto, a series of transverse riffle-plates mounted to swing within the sides of the table, a laterally-movable rod arranged in advance of each riffle-plate, each rod carrying a series of depending fingers and of means for imparting movement to the finger-carrying rods during the longitudinal movement of the table.

6. The combination with the rotary separator eliminating the coarse material, of the longitudinally - reciprocating concentrating-table arranged below the separator, a chute leading from the discharge end of the separator to the upper end of the concentrating-table and delivering the pulp thereto, of devices by means of which the material passing over the surface of the concentrating-table is agitated while permitting the grain-gold to settle, a trough arranged below the discharge end of the table, a drum working therein, and a series of amalgamating-plates secured to and carried by the drum for intercepting the float-gold.

7. The combination of a supporting-frame, a concentrating-table movably mounted thereon, means for reciprocating said table longitudinally, finger-bars movable transversely of the table and mechanism whereby longitudinal movement of the table causes transverse movement of alternate finger-bars in opposite directions, substantially as described.

In witness whereof I have hereunto set my hand.

JOHN B. MOORE.
